VARIABLE AREA MAGNETIC RECORDING APPARATUS

Ralph B. Atkinson, Beverly Hills, and Steven G. Ellis, Van Nuys, Calif.; said Ellis assignor to said Atkinson

Application December 15, 1951, Serial No. 261,892

12 Claims. (Cl. 179—100.2)

This invention relates generally to the magnetic recording of intelligence, and has particular reference to a magnetic recording apparatus for producing a variable area magnetic recording of signals corresponding to such intelligence.

Magnetic recording on a specially designed magnetic tape or wire has long been known and used, and the many advantages of such recording have widened the field of use considerably. More recently, the utility of the magnetic recording processes has been greatly increased by the development of certain methods for making visible magnetic recordings as distinguished from the earlier types of recordings wherein the recorded material was completely invisible.

It is possible to render the magnetic recording visible by flowing finely divided magnetic particles over the magnetic recording so that the particles are held to the record material in varying amounts depending upon the intensity of magnetization of the particular area of the material. A method and apparatus for magnetic reproduction of pictures using this general method of flowing magnetic particles over a magnetized record is the subject of a copending application Serial No. 221,044, filed April 14, 1951, by Ralph B. Atkinson and Steven G. Ellis. As is disclosed in that application, the visible record formed upon the magnetized record material may be transferred to another support to produce a permanent print or copy of the magnetic record. The process of making visible records from magnetic records has been termed "ferrography," and the process has come to be known as the ferrographic process as distinguished from the photographic process wherein light-sensitive materials are employed.

In a copending application Serial No. 250,364, filed October 8, 1951, by Ralph B. Atkinson and Steven G. Ellis, it is pointed out that prior to the invention therein disclosed of an apparatus for making a variable area magnetic recording, ferrography had seldom been used in the recording of technical data because the resulting visible record revealed only areas of different densities, because prior thereto the magnetic recording apparatus in use was capable only of producing a variable density record. Since it is difficult to evaluate differences in intensity, either by observation or physical measurement, the use of the ferrographic process for the recording of technical data was limited almost entirely to those applications where it was desired only to obtain qualitative results.

The aforementioned copending application Serial No. 250,364 discloses an apparatus for producing a variable area recording wherein the height of the record at any given point corresponds to the intensity of the recorded signal. By making such a record visible by the ferrographic process, it is possible to obtain a record comprising an oscillogram of the applied signal. Such a record combines the advantages of a record made by a direct-reading, pen-type oscillograph with the speed of response corresponding to that of the cathode ray oscilloscope.

In addition, the disadvantages of the photographic method of recording encountered in both the mirror-type oscilloscope and cathode ray oscilloscope are avoided.

In the apparatus disclosed in the aforementioned copending application Serial No. 250,364 a variable area recording is obtained by passing the recording medium beneath a recording head which provides a recording gap of substantial length extending transversely of the direction of travel of the recording medium. In one form disclosed in that application, the recording gap is made V-shaped—that is, wider at one end than at the other, thus causing a concentration of the flux at the narrow end of the gap. Thus, at low signal intensities a permanently magnetized record is produced only in that portion of the recording medium passing the narrow end of the gap, whereas at higher signal levels, the flux density is increased across the wider portions of the gap so as to record a correspondingly wider line on the moving recording medium.

While the apparatus disclosed in said aforementioned copending application Serial No. 250,364 is entirely practical, the apparatus nevertheless embodies certain disadvantages residing principally in the difficulty of forming a V-shaped gap of the required accuracy. It will be appreciated that the air gaps used in magnetic recording are extremely small, and a V-shaped gap for producing a variable area magnetic recording may have a minimum width of one-half mil (the term "mil" being used to represent a distance of one one-thousandth of an inch), and a maximum width of perhaps one and one-half mils. Furthermore, in order to achieve a desired recording characteristic, it may be necessary to make the sides of the gap curved as distinguished from the straight sides of a truly V-shaped gap. The use of a curved support for a variable clearance between the recording head and the recording medium disclosed as alternative modifications in said copending application Serial No. 250,364 does not completely obviate the disadvantages and difficulties of construction of the V-shaped gap because they introduce the difficulty of feeding the recording medium over a curved support and also tend to produce loss of definition due to fringing resulting from the spacing of the recording head from the recording medium.

To overcome the above-mentioned disadvantages, this invention provides a variable area recording apparatus utilizing a recording gap of substantial length and uniform width, and eliminates the need for any curved supports for the recording medium or the necessity of spacing the recording head from the record material. Instead, the present invention provides a recording apparatus which is maintained in constant contact with the recording medium throughout the entire length of the elongated recording gap, and provides also for the selection of substantially any desired relationship between the location along the length of the gap and the magnetomotive force across the gap at that location.

It is therefore an object of this invention to provide a magnetic recording apparatus for producing variable area recording which utilizes a recording gap of substantial length and uniform width which is maintained in contact with the recording medium throughout the length of the recording gap.

It is also an object of this invention to provide an apparatus of the character set forth in the preceding paragraph which includes an electromagnet for producing an integrated magnetomotive force across the recording gap as a whole, corresponding to a signal to be recorded, together with means for producing a concentration of magnetic flux across the gap at one end thereof.

It is another object of this invention to provide an apparatus of the character set forth in the preceding paragraph which includes a magnetic circuit external to

said electromagnet in which said circuit includes said recording gap and consists of a plurality of parallel branch circuits crossing said gap at different locations, the reluctance of said branch circuits being a function of the location at which said gap is crossed thereby.

It is an additional object of this invention to provide an apparatus of the character set forth hereinbefore in which means is provided for producing across the recording gap a gap magnetomotive force bearing a ratio to the integrated magnetomotive force which is a function of the location along the length of the gap.

It is also an object of this invention to provide an apparatus of the character set forth hereinbefore which includes a single pole structure of substantial length having its ends connected magnetically to opposite poles of the electromagnet, said pole structure having a substantial reluctance producing on the surface of said structure magnetic pole strengths which vary along the length of said structure.

It is a further object of this invention to provide an apparatus of the character set forth in the preceding paragraph in which said pole structure has a cross section including a V-shaped portion to define at the apex of said V-shape a narrow edge for engaging the recording medium.

It is also an object of this invention to provide a magnetic recording apparatus for producing variable area recordings which includes an electromagnet for producing an integrated magnetomotive force across the recording gap as a whole, corresponding to a signal to be recorded, and which includes a pole structure comprising a pair of adjacent pole members separated by a recording gap of substantial length and uniform width, together with a magnetic circuit means connecting opposite poles of said electromagnet to the ends of corresponding pole members, said pole members having a reluctance from end to end comparable to the reluctance of said recording gap.

It is another object of this invention to provide an apparatus of the character set forth in the preceding paragraph in which the reluctance per unit length of said pole members varies along the length thereof.

It is another object of this invention to provide an apparatus of the character set forth in the preceding paragraph in which said pole members comprise a plurality of magnetic members spaced from each other by air gaps crossing said pole members.

It is an additional object of this invention to provide an apparatus of the character set forth in the preceding paragraphs in which the pole members have a varying cross-sectional area.

It is a still further object of this invention to provide an apparatus of the character set forth in the preceding paragraphs in which the area per unit length of said recording gap varies along the length thereof.

Other objects and advantages of this invention will be apparent from a consideration of the following specification, read in connection with the accompanying drawings, wherein:

Essentially, this invention contemplates the use of a 50 magnetic tape transport means, a magnetic recording head of special construction against which the tape bears and across which it passes while being transported, together with associated electrical apparatus for supplying an appropriate signal to the recording head. Such an apparatus is illustrated in Fig. 1 as comprising a cabinet or housing 30 which encloses a suitable electric motor (not shown) or other source of motive power for driving film sprockets or rollers 31 for moving a transportable magnetic tape 32 past a recording head 33. As the tape 32 is moved past the recording head 33, it is maintained in constant and intimate contact therewith by a roller 34 or pressure pad of usual and conventional construction.

To facilitate transporting the tape 32 in the manner described, the same is preferably perforated in the general manner of motion picture films. While unperforated tape may be used, and while the tape 32 may be of substantially any desired width, a preference is expressed for a tape having the width and sprocket hole arrangement of conventional 35 mm. film because of the ready availability of suitable sprockets, reels, and the like.

The drive means for rotating the sprockets 31 is arranged preferably to transport the tape at a constant linear speed past the recording head 34 so as to permit ready and accurate measurements with respect to time.

75 When so transported, the tape 32 is fed from a suitably

supported supply reel 35, and after recording is wound upon a suitable take-up reel 36.

The recording head 33, which is of special construction, may be constructed in accordance with the principles illustrated in Fig. 2 to include an electromagnet 40, a pair of pole members 41 and 42 and magnetic circuit means 43 and 44 for connecting opposite poles of the electromagnet 40 to adjacently disposed ends of the pole members 41 and 42, respectively.

At the outset, it should be recognized that the drawings accompanying this application are largely diagrammatic, the arrangement of parts and details of construction shown having been selected with a view to best illustrating the principles of the invention. Different arrangements and details of construction which will be obvious to those skilled in the art may be employed to embody the principles of this invention in more compact structures designed also to facilitate the manufacture thereof. Furthermore, it should be recognized that the drawings are not to scale, and are mal-proportioned for the purpose of clearly illustrating the essential features of construction, air gaps and certain structural parts having widths and thicknesses of the order of magnitude of one mil being represented in the drawings as being of substantial width and thickness for the purpose of clearly illustrating the construction.

The electromagnet 40 may be of substantially conventional construction, wound to provide a number of turns sufficient to produce a substantial magnetomotive force and to provide an impedance appropriate to the source of signal to be recorded. The magnet circuit members 43 and 44 may also be constructed along conventional lines, preferably being laminated to minimize hysteresis and eddy current losses, and are preferably made of a high-permeability, low-loss material. The members 43 and 44 are proportioned to provide a reluctance which is low compared to the reluctance of the pole structures 41, 42 and low compared to the reluctance of the recording gap. The magnetic circuit members 43 and 44 are connected as shown to one end of each of the pole structures 41 and 42 so as to provide between said ends a magnetomotive force which is substantially equal to that appearing at the pole of the electromagnet 40.

The pole structures 41 and 42 are secured in side-by-side relation to each other to define therebetween a recording gap 45. The recording gap 45 is made of uniform width, preferably of the order of magnitude of one mil, and is made with a length (equal to the length of the pole structures 41, 42) appropriate to the width of the recording medium 32. When used with 35 mm. film, the recording gap may have a length of about one inch.

A recording gap 45 of uniform width throughout the length thereof is most easily obtained by the use of a metallic spacer member having a thickness equal to the desired gap width and formed of a suitable non-magnetic material such as brass or beryllium copper. Such sheet material is readily available in a form sometimes known as "shim" stock in a wide range of thicknesses ranging upwards from one-half mil. Such material is eminently suited to use as the spacer member 46 because of its ready availability and, what is more important, because of the great uniformity of its thickness and the accuracy with which the actual thickness of the material corresponds to its nominal thickness dimension.

Each of the pole structures 41 and 42 comprises a plurality of magnetic members 47 spaced from each other by interposed air gaps 48. As in the case of the recording gap 45, the air gaps 48 are most easily provided by sandwiching sheets of non-magnetic material between adjacent magnetic members 47. The magnetic members 47 are preferably formed of a high-permeability material characterized by a small hysteresis loss.

The magnetic members 47 and the alternate non-magnetic spacers 48 are stacked sandwich-like one upon the other to provide a pole structure 41, 42 of the required

length. These members may be held in the positions in which they are placed by means of a longitudinally extending non-magnetic securing means such as the brass screws 49 shown in Fig. 3, the screws 49 being passed through suitable apertures formed in each of the members 47 and 48 and secured to the magnetic members 43 and 44 as by means of a threaded connection such as is shown at 50. The outer ends of the pole members 41 and 42 may be interconnected by means of a non-magnetic cross tie 51 held in place also by the screws 49. Additional non-magnetic clamping members may be used to secure the two pole members 41 and 42 to each other as desired, such additional clamping structures being omitted from Fig. 2 in the interests of clarity.

15 It has been found convenient in constructing the pole structure comprising the pole members 41, 42 and the recording gap spacer 46 as shown in Fig. 2 by first assembling the entire structure as a unit and then grinding or otherwise machining the undersurface of the structure to a smooth surface suitable for bearing against the surface of the moving recording medium.

20 It is believed that the magnetic members 47 should be materially thicker than the non-magnetic spacers 48. Excellent results have been secured, for example, using magnetic members 47 having a thickness of 20 mils and using non-magnetic spacers 48 having a thickness of 1 mil.

25 The manner in which the apparatus illustrated in Fig. 2 operates to provide a variable area magnetic recording may perhaps be best understood by having reference to Fig. 4 which illustrates diagrammatically the equivalent magnetic circuit of the apparatus shown in Fig. 2. In Fig. 4 each of the pole members 41, 42 is illustrated as consisting of six "stages" marked *a* to *f* inclusive, each stage consisting of a magnetic member 47 and an associated air gap 48 separating the member 47 from the next adjacent such member. The reference letters *a-f* are used herein as suffixes to denote the location of particular elements. Thus, 47*e* represents the magnetic member 47 in stage *e*, and similarly 45*b* represents the recording air gap between oppositely positioned magnetic members 47 in stage *b*.

30 Because of the low reluctance of the magnetic circuit members 43 and 44, the full magnetomotive force generated by the coil 40 may be considered as applied between the first two magnetic members 47*a*. It will be seen by an inspection of Fig. 4 that this full magnetomotive force exists across the first portion 45*a* of the recording gap. It will be equally apparent that the flux density across the recording gap section 45*b* will be less than that across the gap section 45*a*, because in addition to overcoming the reluctance of the recording gap 45*b*, such flux must also overcome the reluctance of the two air gaps 48*a* in the pole members 41 and 42, respectively. Similarly, it will be seen that the flux density across a more remote recording gap section such as the section 45*d*, for example, will be still further reduced, since the flux passing across that portion of the recording gap must overcome not only the reluctance of the gap section 45*d*, but also the reluctance of the gaps 48*a*, 48*b*, 48*c* of the pole member 41, and of the air gaps 48*c*, 48*b*, and 48*a* of the pole member 42.

35 An analogous electrical circuit is illustrated in Fig. 5, in which the source of magnetomotive force is replaced by the battery *E* providing an electromotive force. The 40 electrical conductors are analogous to the portions of the recording head which are made of magnetic material, and the resistances *R*_a—*R*_e correspond to the air gaps 48*a*—48*e*. The cross connections *R*_{ga}—*R*_{gf} correspond to the reluctances of the air gaps 45*a*—45*f*. In Fig. 5 it will be seen that the full electromotive force *E* is applied across the first resistance *R*_{ga}. A somewhat smaller voltage is applied across the second resistance *R*_{gb} due to the voltage drops in the two resistances *R*_{ga} produced by the current passing through the cross-connected resistances *R*_{gb}—*R*_{gf}. In like manner the voltage across

the resistance R_{gc} is less than that across the resistance R_{gb} due to the voltage drops through the resistances R_b produced by the sum of the currents drawn by the cross-connected resistances R_{gc} — R_{gf} .

In Fig. 6 there is plotted a family of four curves 51, 52, 53, and 54 representing the flux density, or alternatively the magnetomotive force, existing across the recording gap 45 as measured at different positions along the length of the gap, the origin of the curve being taken at the innermost end of the pole members 41 and 42—that is, at the ends thereof which are connected directly to the magnetic circuit members 43 and 44. The four curves 51–54 represent the flux densities produced by four different intensities of magnetization produced by the coil 40. The horizontal dotted line 55 represents a threshold level of gap magnetomotive force below which no permanent magnetization of the recording medium will be produced. Curve 51 therefore represents the minimum signal level which, when applied to the coil 40, will produce any permanent magnetic record, and by observing that the intersection of the curve 51 with the line 55 occurs at the origin, it will be seen that this represents the limiting condition producing a permanent record only at the extreme edge of the tape. Curve 52 represents a higher signal level, and it will be observed that the curve crosses the line 55 at the point marked 56. Thus in the region to the left of the point 56 the magnetomotive force across the gap will be sufficient to produce a permanent magnetic record, whereas in the region to the right of the point 56 the magnetizing intensity will be insufficient. Thus a signal of a magnitude such as is represented by the curve 52 will cause a permanent recording to be made for a distance transversely of the tape approximating one-third the length of the gap.

The curves 53 and 54 respectively intersect the threshold level line 55 at the points marked 57 and 58, representing, respectively, the intensities of magnetization required to produce permanent magnetic recordings extending, respectively, for two-thirds the length of the gap and for the full length of the recording gap.

Whether or not a given magnetizing force will produce a permanent magnetic record and the intensity of magnetization of that record depends, of course, upon the magnetic characteristics of the recording medium. There is illustrated in Fig. 7 a characteristic curve which is representative of the magnetic characteristics of magnetic recording media generally. In Fig. 7 there is shown a curve 60 which represents the relation between the magnetizing force applied to a magnetic recording medium and the resulting residual induction or permanent magnetization after the magnetizing force is removed. Assuming a neutral recording medium, the curve starts at the origin representing zero residual induction when no magnetizing force is applied. The curve rises slowly to a point marked 61, the abscissa of which is represented by the dimension line bearing the reference character 62, and the ordinate of which is represented by the dimension line bearing the reference character 63. The dimension 63 represents the threshold residual induction and constitutes that degree of permanent magnetization which will produce a definite though low intensity of permanent magnetism in the magnetic recording medium. The dimension line 62 represents the amount of magnetizing force which must be applied to produce such a threshold condition.

From the point 61 the curve rises steeply to a high value of residual induction, and then curves to the right with a decreasing slope, finally becoming parallel to the horizontal axis representing the maximum possible residual induction which can be produced regardless of the magnitude of the magnetizing force.

The curve 60 is similar to the H and D curve used to represent the properties of photographic materials, the dimension 62 corresponding to the inertia of photographic materials, and the slope of the steeply rising

portion corresponding to the Gamma of the photosensitive material.

Ideally, the magnetic recording medium selected for use with a variable area magnetic recording head of the type herein described has a small inertia—that is, a short dimension line 62, so that the amount of magnetizing force necessary to produce a permanent record need not be too great. The steeply sloping part of the curve 60 should have as steep a slope as possible so that once the magnetizing force exceeds the threshold value, the residual induction will rise rapidly with small increases in magnetizing force so as to produce a record which in appearance, after being coated with the visible magnetic particles, displays a clean, well-defined line of demarcation between those portions which have been permanently magnetized and those which have not.

In Fig. 7 the dashed line 55a passing vertically through the point 61 represents the threshold value of magnetizing force which is represented in Fig. 6 by the dashed line 55.

Thus it is seen from a comparison of Figs. 6 and 7 that as the energy supplied to the magnetizing coil 40 is increased, no permanent magnetic record is produced until the magnetizing force reaches the mentioned threshold value for the portion of the recording gap 45 nearest the magnetic circuit members 43 and 44, such level of magnetizing force being represented by the curve 51 of Fig. 6. Thereafter, as the energy supplied to the coil 40 is increased, the length of that portion of the recording gap 45 across which the magnetizing force is greater than the threshold value correspondingly increases until, at the maximum signal condition, the magnetomotive force across the gap 45 is at all points along the length thereof higher than the threshold value.

Fig. 8 illustrates the type of record produced by the described operation of the magnetic recording head shown in Fig. 2 when there is applied to the electromagnet 40 thereof a signal of the character illustrated graphically in Fig. 9.

The signal represented by Fig. 9 constitutes an alternating electrical potential of a given fundamental frequency and carrying a substantial second harmonic component resulting in the production of two distinct positive peak signals 64 and 65 followed by two corresponding negative peak signals 66 and 67. Thereafter the cycle repeats itself at the fundamental frequency. The magnetic record which is produced is of the character illustrated in Fig. 8 consisting of the positive peaks 64 and 65 followed by what may be termed a rectified representation of the negative half of the cycle resulting in the peaks 66' and 67'. The apparent polarity reversal results from the fact that the magnetic material which is flowed across the magnetized recording medium adheres equally well to both polarities of magnetization, and does not distinguish between those elemental areas having a north polarity and those having a south polarity. Once this fact is recognized, the wave form of the original signal is quite clearly seen by inspection of the record produced. The important consideration is that the length of the visible recording, measured upwardly in Fig. 8 from a base line 68, corresponding to that end of the gap 45 situated nearest the magnetic circuit members 43 and 44, corresponds to the instantaneous amplitudes of the signal applied to the electromagnet.

The record produced is represented in Fig. 8 as being characterized by narrow blank spaces 69 corresponding to the points at which the signal level is below the aforementioned threshold value. This is consistent with the initial assumptions made thus far in describing the operation of the apparatus in which a neutral magnetic recording medium is assumed, and in which the signal is applied directly to the electromagnet 40 without the use of any bias currents or modulated carrier signals. These blank spaces are readily eliminated through the application of any of a number of well-known magnetic recording

techniques such as the use of a premagnetized recording medium, the use of either direct or high-frequency bias currents, or by the use of a carrier signal of high frequency upon which the signal to be recorded is applied as an amplitude modulation.

Preferably, the recording head is so constructed as to produce a linear relationship between the amplitude of the applied signal and the length of the recording gap which develops a magnetizing force in excess of the threshold value. If such a linear relationship is established, then the visible record produced represents truly the wave form or amplitude variations of the applied signal.

As will be apparent to those skilled in the art, this does not necessarily require a linear relation between the magnetizing force and the distance along the gap at which that magnetizing force is measured. In fact, as may be seen from an inspection of Fig. 6, the characteristic is most probably curved so as to be concave upwards, but the degree of curvature and the shape of the curve will depend upon many factors, not the least important of which is the characteristics of the recording medium used.

An upwardly concave characteristic is inherent in the structure shown in Fig. 2. By resort to the analogous electrical case represented by Fig. 5, it can be shown that if the reluctance of each of the air gaps 48 is made equal to each other and equal also to the reluctance of the recording gap 45, a curve form which is concave upwards and which is very sharply curved near the beginning results. If the effects of stray fields, fringing, and saturation are ignored, the flux distribution across the gap will be such that the flux across each gap section 45a, 45b, etc. will be approximately one-fourth that across the next preceding section. A curve having such a great curvature would quite likely fail to produce the desired linear relationship between the amplitude of the input signal and the length of the recorded line. However, in practice it is found that the saturation and fringing effects cannot be ignored, and that these effects tends to flatten the curve considerably. It can be seen, for example, that as the magnetizing force across the gap 45a increases with a corresponding increase in flux density, those portions of the magnetic elements 47 immediately adjacent the air gap 45 will become saturated, with a corresponding decrease in permeability and a corresponding increase in reluctance, whereas those portions spaced from the gap will not be so saturated. This tends to divert the flux farther along the pole piece, and so causes the flux across each of the gap sections 45a, 45b, etc. to be a larger fraction of the flux density across the next preceding gap section than the simplified calculations would indicate.

The shape of the curve can also be changed by changing the ratio of the reluctance of the air gaps 48a, 48b, etc. with respect to the reluctance of the recording gap sections 45a, 45b, etc. This is accomplished by adjusting the thickness of the spacer elements 48 and 46.

The reluctance of the pole members 41 and 42 may also be caused to vary along the length thereof by appropriate selection of the thickness of the magnetic members 47 and the spacing members 48. In Fig. 10, for example, there is illustrated diagrammatically an arrangement utilizing spacer members 48 of like thickness to separate magnetic members 47, the thickness of which diminishes progressively as the outer end of the structure is approached. A different though somewhat similar arrangement is illustrated in Fig. 11, wherein the magnetic members 47 are all of the same thickness, but wherein the thickness of the non-magnetic spacers 48 is caused to progressively reduce as the outer end of the structure is approached.

Fig. 12 represents a typical test record produced by the operation of the apparatus thus far described. Fig. 12 comprises a visible record of the frequency response

characteristic of an amplifier. Such a record may be produced by moving the recording medium 32 past the recording head 33 at a constant speed while there is applied to the input of the amplifier under test a signal of constant amplitude whose frequency is caused to vary with time from a very low frequency to a very high frequency. The output of the amplifier is connected to the electromagnet 40 of the recording head, and the voltage applied to the electromagnet will vary as the amplification of the amplifier varies as a function of the applied frequency.

The magnetic record thus produced reveals, when treated with the visible magnetic material as hereinbefore described, a curve of the character shown in Fig. 12 and representing diagrammatically the frequency response characteristic of the amplifier. As is shown in Fig. 12, the low frequency signals represented by the half-cycle peaks 70, 71, 72 etc. is indicated as having been somewhat attenuated by the amplifier under test. A relatively flat region 73 is shown at frequencies of an intermediate range with a maximum gain being revealed at the upper end 74 of the middle frequency range. A rather sharp cut-off 75 at the high frequency end of the spectrum is revealed.

A modified form of recording head 33 is illustrated in Fig. 13. The recording head there shown is in many respects similar to that illustrated in Fig. 2, employing an electromagnet 40 for producing a magnetomotive force which is conveyed by means of the aforementioned magnetic circuit members 43 and 44 to the inner ends of a pair of pole members 81 and 82. The members 81 and 82 are separated to define a recording gap 83, which gap may be defined by a non-magnetic spacer 84 formed of suitable material such as brass or beryllium copper.

As in the previously-described modification, the magnetic circuit members 43 and 44 are made of high-permeability material and of ample cross section so as to provide a path of extremely low reluctance to thereby apply to the inner ends of the pole members 81 and 82 a magnetomotive force which is substantially equal to that generated by the electromagnetic 40. The members 81 and 82, however, are so constructed as to have an appreciable reluctance. This may be accomplished by suitably proportioning the cross-sectional area of the members, and by a suitable selection of the material from which the members are made, such selection being made with reference to the magnetic properties of the material.

The structure thus formed is very similar to that illustrated in Fig. 2, and may be likened to the results achieved by making the thickness of the magnetic members 47 and the spacer members 48 of Fig. 2 infinitesimally small. The device operates in a manner identical to that described with reference to Fig. 2, and operates to produce similar results.

Adjustment of the shape of the characteristic curve may be made by varying the cross-sectional area of the members 81 and 82, for example as by tapering the members in thickness as is indicated by the members 81a and 82a of Fig. 14. Such a tapering of the members provides a reduced reluctance at the inner end of the structure, and an increased reluctance at the other end, thus tending to shift outwardly the threshold value of magnetomotive force produced across the recording gap by a given magnetomotive force generated by the electromagnet 40.

Somewhat similar results may be achieved by tapering the pole members in height as is represented by the pole members 81b and 82b of Fig. 15.

Figs. 16 and 17 illustrate still another way in which a characteristic curve of desired form may be achieved. In the modification shown in Figs. 16 and 17 a pole structure comprising the pole members 81c and 82c separated by the spacer member 84c are first produced which are

similar in all respects to that shown in Fig. 13. Thereafter, the upper surface of the members 81 and 82 is milled away to provide a slot or groove 86 extending downwardly from the upper surface of the members 81c and 82c, the depth of the slot 86 being varied along the length of the members to provide a curved surface 87 such as is shown in Fig. 16 defining the bottom of the slot.

Assuming that the recording air gap 83 is one mil wide and that the members 81c and 82c have a horizontal thickness of about 20 mils, it is seen that the width of the air gap may be increased by the slot 86 by a factor of from five to ten times without a material reduction in the cross-sectional area of the pole members 81c and 82c. This expedient serves to concentrate the flux across the air gap 83 at the lower surface of the pole structure, particularly near the outer end thereof. This tends to flatten out the characteristic curve of the recording head, since only that portion of the flux which crosses the gap near the undersurface of the structure is effective in magnetizing the recording medium.

Fig. 19 represents diagrammatically the type of visible record produced by a modified recording head 33a represented in Fig. 18. The recording head 33a is identical to that illustrated in Fig. 13, except for providing a second pole structure 81', 82' identical to the pole structure 81, 82, but extending outwardly to the rear from the magnetic circuit members 43, 44. The pole structures are, of course, made somewhat shorter than in the form shown in Fig. 13 if the device is to be used with a recording medium 32 of the same width.

It will be appreciated that with the structure shown in Fig. 18, when the energy applied to the electromagnet 40 is increased the first recording is made at the center of the recording medium where the two pole structures 81, 82 and 81', 82' are joined to each other and to the magnetic circuit members 43, 44. This point defines a neutral axis which is represented in Fig. 19 by the broken line 90. As the signal level is increased, the length of the line permanently magnetizes, increases outwardly in both directions from the neutral axis 90.

Thus, when a signal of the character represented in Fig. 9 is applied to the recording head shown in Fig. 18, there results a record of the type shown in Fig. 19 wherein the positive peaks 64 and 65 are reproduced and are accompanied by mirror images 64' and 65' thereof. Similarly, the negative peaks 66 and 67 are recorded as well as the positive mirror images 66' and 67'.

There is illustrated in Figs. 20, 21, and 22 a variable area magnetic recording head 33b of somewhat different type from those hereinbefore described. The recording head 33b includes an electromagnet 100 surrounding a suitable magnetic core 101 which is connected by means of magnetic circuit members 102 and 103 to opposite ends of a single pole structure represented generally by the reference character 104. The core 101 and magnetic circuit members 102 and 103 are made of high-permeability, low hysteresis loss material, and are given an ample cross section so that the magnetomotive force generated in the core 101 by the coil 100 is applied without appreciable attenuation to opposite ends of the pole member 104. As may be seen from Figs. 20 and 21, the pole member 104 comprises a plurality of thin magnetic members 105 separated from each other by non-magnetic spacer members 106 formed of brass, beryllium copper, or other suitable material. The entire assembly of magnetic members 105 and spacer members 106 may be threaded onto a pin 107 suitably secured in appropriate apertures provided at the lower ends of the magnetic circuit members 102 and 103.

The pole member 104 is preferably given a triangular cross section as may be seen in Fig. 22 so as to define a relatively sharp downwardly directed edge 108 which is caused to bear against the upper surface of the record-

ing medium 32. The edge 108 is, of course, positioned directly above the pressure pad 34.

The operation of the recording head 33b may perhaps best be understood by assuming that a direct current is passed through the electromagnet 100 so as to provide a north magnetic pole at the end of the structure adjacent the magnetic member 102, and a corresponding south magnetic pole at the end adjacent the member 103. The pole structure 104 has a substantial reluctance due to the accumulated air gaps provided by the spacer members 106, and when so externally excited, appears to have the characteristics of a permanent bar magnet displaying a north magnetic pole at one end, and a south magnetic pole at the other. The center of the structure exhibits a pole strength of zero, and the pole strength increases from the center toward the ends, becoming stronger and stronger in north polarity as the end adjacent the member 102 is approached, and stronger and stronger in south polarity as the end adjacent the member 103 is approached. The resulting local magnetic poles produced along the edge 108 of each of the magnetic members 105 serves to permanently magnetize the recording medium 32 in the same manner that a strongly magnetized bar magnet or like structure would magnetize the material.

It is seen that as the current in the electromagnetic 100 is increased from zero, the threshold magnetizing force is first reached at the ends of the pole structure 104. The location of this threshold value moves toward the center as the current is increased. This produces a record similar to that illustrated in Fig. 8, but differing therefrom in providing a duplicate mirror image recording extending inwardly toward the center from the opposite edge of the recording medium.

The embodiment of the invention just described and illustrated in Figs. 20, 21, and 22, while operating by a somewhat different mode of operation from the modifications described previously thereto, is nevertheless a great deal like those previously described modifications in the underlying principles of the invention. It will be observed that the magnetic circuit members 102 and 103 each operate to apply to one end of the pole structure 104 without appreciable attenuation the magnetizing force generated by the electromagnet. Like the pole members of the first-described modifications, the pole member 104 is made with a relatively high reluctance so as to cooperate with the backing member 34 in producing between the knife edge 108 and the backing member 34 a magnetizing force which varies in magnitude along the length of the pole member 104.

In this respect it will be observed that the device shown in Figs. 20-22 operates primarily to magnetize the recording medium perpendicularly as distinguished from the lateral magnetization produced by the first-described forms of the invention.

It will be noted also that the shape of the recording characteristic of the recording head 33b of Fig. 20 may be altered by the appropriate selection of the thickness of the magnetic members 105 and the spacing members 106, as has hereinbefore been described in connection with Figs. 10 and 11.

Also, as in the previously described modifications, the laminated structure illustrated in Figs. 20 and 21 may be replaced with a single homogeneous member of suitably high reluctance per unit length. Such a suitably high reluctance may be obtained in this form of the invention, as in the previously described forms, through appropriate selection of material. Such members may, for example, be formed of a suitable synthetic resin heavily impregnated with powdered magnetic material such as iron dust. Somewhat similar structures can be made from powdered magnetic materials which are bonded to each other by a suitable adhesive or by means of a sintering or semi-sintering process.

In using any of the recording heads hereinbefore de-

scribed, the pole members are preferably held lightly in contact with the surface of the recording medium, and disposed with the length of the pole members extending transversely of the direction of movement of the recording medium. Also, to prevent local demagnetization and to concentrate the effective magnetizing force in the region of the recording gap, the pole structures illustrated in each of Figs. 2, 13, 14, 15, 16, 17, and 18 are preferably formed with a partially cylindrical or downwardly convex surface, or, alternatively, the recording medium is drawn over an oppositely curved surface, so as to limit the area of contact of the pole members with the recording medium to a narrow band in the immediate vicinity of the recording gap.

From the foregoing, it will be observed that this invention provides an apparatus for producing a variable area magnetic recording, and that the apparatus includes a variable area magnetic recording head characterized by the employment of a recording air gap of uniform width and substantial length as distinguished from the disclosures contained in the aforementioned copending application Serial No. 250,364 wherein the air gap is given a V-shape, or wherein the recording pole pieces are spaced variously from the surface of the recording medium. The invention described herein avoids certain of the disadvantages inherent in the apparatus disclosed in that copending application, and provides various types of structures which are susceptible to ready and accurate manufacture. Furthermore, as will have been observed, the construction is such as to permit the shape of the recording characteristic curve to be selected substantially at will. This is accomplished by appropriately selecting the reluctances of the various parts of the magnetic circuit, and does not require any changes in the configuration or dimensions of the recording gap.

While an attempt has been made herein to disclose and explain the underlying principles of the invention, no attempt has been made to give precise directions for the determination of the dimensions of the various parts of the magnetic apparatus for the reason that experience has indicated that these dimensions and characteristics are more quickly determined by trial and error than by calculation since it is not possible in calculations of this type to take into account all of the factors which determine the ultimate results. It is believed, however, that the principles of the invention have been outlined with sufficient clarity to permit one skilled in the art to make, without difficulty, a variable area magnetic recording head of the type herein described, and to permit such a head to be used for the making of variable area recordings.

It will be observed that this invention provides variable area magnetic recording heads for making various types of records, such as are illustrated for example in Figs. 8, 12, and 19, as well as the type of record herein described as produced by the head illustrated in Fig. 20. In this connection it is to be noted that a double-ended head such as is shown in Fig. 18 for producing records of the character represented by Fig. 19 may utilize pole members 81, 82 and 81', 82' of any of the types and incorporate, as desired, any of the features of construction previously described with reference to Figs. 2 to 17, inclusive.

Attention is directed particularly to the fact that by the use of the apparatus herein disclosed, it is possible to make visible records constituting oscilloscopes of the signal applied to the recording head, and that these oscilloscopes may be rendered immediately visible for study without the delay and difficult processing attendant upon the use of photographic recording methods.

While the various preferred embodiments of this invention have been illustrated and described herein, the invention is not to be limited to the details illustrated and described, except as defined in the appended claims.

We claim:

1. In a variable area magnetic recording head for

producing on a longitudinally moving elongated magnetizable recording medium a permanent magnetic record of an electrical signal in which the height of said record transversely of said medium varies in correspondence with variations of the instantaneous amplitude of said signal, the combination of: an electromagnetic for producing a magnetomotive force corresponding to said signal; a magnetic pole structure of substantial length disposed transversely of said recording medium with one surface in contact with said medium, said pole structure having a relatively high reluctance from end to end and comprising a plurality of thin separate magnetic members disposed in side by side relation with their thickness dimension parallel to the length of said structure, said magnetic members being held in spaced relation to each other by non-magnetic spacer members interposed between adjacent magnetic members; and magnetic conductor means of low reluctance connected between one end of said electromagnet and one end of said pole structure to magnetize said end of said pole structure in accordance with said magnetomotive force produced by said electromagnet, each of said magnetic members being magnetized in an amount dependent upon the magnetomotive force produced by said electromagnetic and the distance of said magnetic member from said one end of said pole structure, whereby said recording medium is magnetized along the length of said pole structure to a varying degree dependent upon the amplitude of said signal and the distance from said one end of said pole structure.

2. In a variable area magnetic recording head for producing on a longitudinally moving elongated magnetizable recording medium a permanent magnetic record of an electrical signal in which the height of said record transversely of said medium varies in correspondence with variations of the instantaneous amplitude of said signal, the combination of: an electromagnet for producing a magnetomotive force corresponding to said signal; a magnetic pole structure of substantial length disposed transversely of said recording medium with one surface in contact with said medium, said pole structure having a relatively high reluctance from end to end and comprising a plurality of thin separate magnetic members disposed in side by side relation with their thickness dimension parallel to the length of said structure, said magnetic members being held in spaced relation to each other by non-magnetic spacer members interposed between adjacent magnetic members, the thickness of said magnetic members varying progressively from one end of said structure to the other; and magnetic conductor means of low reluctance connected between one end of said electromagnet and one end of said pole structure to magnetize said end of said pole structure in accordance with said magnetomotive force produced by said electromagnet, whereby said recording medium is magnetized along the length of said pole structure to a varying degree dependent upon the amplitude of said signal and the distance from said one end of said pole structure.

3. In a variable area magnetic recording head for producing on a longitudinally moving elongated magnetizable recording medium a permanent magnetic record of an electrical signal in which the height of said record transversely of said medium varies in correspondence with variations of the instantaneous amplitude of said signal, the combination of: an electromagnet for producing a magnetomotive force corresponding to said signal; a magnetic pole structure of substantial length disposed transversely of said recording medium with one surface in contact with said medium, said pole structure having a relatively high reluctance from end to end and comprising a plurality of thin separate magnetic members disposed in side by side relation with their thickness dimension parallel to the length of said structure, said magnetic members being held in spaced relation to each other by non-magnetic spacer members interposed between adjacent magnetic members, the thickness of said non-

15

magnetic spacer members varying progressively from end to end of said pole structure; and magnetic conductor means of low reluctance connected between one end of said electromagnet and one end of said pole structure to magnetize said end of said pole structure in accordance with said magnetomotive force produced by said electromagnet, whereby said recording medium is magnetized along the length of said pole structure to a varying degree dependent upon the amplitude of said signal and the distance from said one end of said pole structure.

4. In a variable area magnetic recording head for producing on a longitudinally moving elongated magnetizable recording medium a permanent magnetic record of an electrical signal in which the height of said record transversely of said medium varies in correspondence with variations of the instantaneous amplitude of said signal, the combination of: an electromagnet for producing a magnetomotive force corresponding to said signal; a magnetic pole structure of substantial length disposed transversely of said recording medium with one surface in contact with said medium, said pole structure having a relatively high reluctance from end to end and comprising a plurality of thin separate magnetic members disposed in side by side relation with their thickness dimension parallel to the length of said structure, said magnetic members being held in spaced relation to each other by non-magnetic spacer members interposed between adjacent magnetic members, said magnetic members being of equal thickness and said non-magnetic members being of equal thickness and holding said magnetic members in uniform spaced relation; and magnetic conductor means of low reluctance connected between one end of said electromagnet and one end of said pole structure to magnetize said end of said pole structure in accordance with said magnetomotive force produced by said electromagnet, whereby said recording medium is magnetized along the length of said pole structure to a varying degree dependent upon the amplitude of said signal and the distance from said one end of said pole structure.

5. In a variable area magnetic recording head for producing on a longitudinally moving elongated magnetizable recording medium a permanent magnetic record of an electrical signal in which the height of said record transversely of said medium varies in correspondence with variations of the instantaneous amplitude of said signal, the combination of: an electromagnet for producing a magnetomotive force corresponding to said signal; a pair of magnetic pole members of substantial length disposed in closely spaced side-by-side relation to define therebetween a narrow recording air gap of uniform width, one surface of each of said pole members adjacent said gap being in contact with said recording medium, said pole members being disposed to extend the length of said gap transversely of said recording medium, each of said pole structures having a relatively high reluctance from end to end; and a pair of magnetic conductors of low reluctance connecting the ends of said electromagnet respectively to adjacently disposed one ends only of said pole members at one end of said gap

16

to oppositely magnetize said ends in accordance with said magnetomotive force produced by said electromagnet, whereby said recording medium is magnetized long the length of said gap to a varying degree dependent upon the amplitude of said signal and the distance from said one end of said gap.

6. A variable area magnetic recording head according to claim 5 wherein the reluctance per unit length of each of said magnetic pole members is uniform from end to end thereof.

7. A variable area magnetic recording head according to claim 5 wherein the reluctance per unit length of each of said magnetic pole members varies progressively from one end of said members to the other end thereof.

15. 8. A variable area magnetic recording head according to claim 5 wherein each of said magnetic pole members comprises a plurality of thin individual magnetic members disposed in side-by-side relation with their thickness dimension parallel to the length of said pole members, and wherein said individual magnetic members are held in spaced relation to each other by interposed spacer elements formed of non-magnetic material and placed between each of said magnetic members and the magnetic members adjacent thereto.

20. 9. A variable area magnetic recording head according to claim 8 wherein the thickness of said individual magnetic members varies progressively from one end of said pole members to the other end thereof.

25. 10. A variable area magnetic recording head according to claim 8 wherein the thickness of said non-magnetic spacing elements varies progressively from one end of said pole members to the other end thereof.

11. A variable area magnetic recording head according to claim 5 wherein said recording air gap is defined by a thin sheet of non-magnetic material placed between said adjacently disposed pole members and securely clamped between the adjacently disposed faces thereof.

12. A variable area magnetic recording head according to claim 5 wherein each of said magnetic pole members comprises a plurality of thin individual magnetic members of equal thickness disposed in side-by-side relation with their thickness dimensions parallel to the length of said pole members, and wherein said individual magnetic members are held in uniform spaced relation to each other by interposed spacer elements of equal thickness formed of non-magnetic material and placed between each of said magnetic members and the magnetic members adjacent thereto.
